[57] ABSTRACT

A capacitor discharge type contactless ignition system for an internal combustion engine is provided in which the stored charge on a capacitor adapted to charge and discharge in one direction only, is discharged through the primary winding of an ignition coil, thus inducing a high voltage in the secondary winding of the ignition coil and providing an ignition spark to a spark plug connected to the secondary winding. The ignition system is so designed that any undesired storage action of the capacitors can be prevented to thereby ensure an excellent ignition advance characteristic and at the same time the developed voltage on the capacitors can be easily made uniform to thereby prevent any misoperation of the engine and ensure a reliable operation thereof.

**CAPACITOR DISCHARGE TYPE CONTACTLESS
IGNITION SYSTEM FOR INTERNAL
COMBUSTION ENGINES**

BACKGROUND OF THE INVENTION

1. Field of the Invention

The present invention relates to a capacitor discharge type contactless ignition system for an internal combustion engine wherein the charge on a capacitor adapted to charge and discharge in one direction only, is discharged through the primary winding of an ignition coil, thereby inducing a high voltage in the secondary winding of the ignition coil and providing an ignition spark to a spark plug connected to the secondary winding.

2. Description of the Prior Art

In known ignition systems of this type, a capacitor charging coil charges a capacitor in one direction only and the charge on the capacitor is discharged through the primary winding of an ignition coil by the conduction of a semiconductor switching element such as a thyristor or transistors, whereby a high voltage is induced in the secondary winding of the ignition coil and thus an ignition spark is provided to a spark plug. On the other hand, in order to increase the generated output of a lamp load power supply coil by the same revolving field as for the capacitor charging coil, it is necessary to increase the number of poles on the revolving field to more than four, e.g., four, six, eight and so on.

However, if the number of poles on the revolving field is increased to four or more, more than two cycles of the output will be generated from the capacitor charging coil and thus, if the output of the capacitor charging coil is subjected to half-wave rectification to charge the capacitor, two capacitor charging half waves will be generated for each rotation of the engine so that following the generation of the required ignition spark, the capacitor will be recharged by the next capacitor charging half wave of the output of the capacitor charging coil. Thus, if, during such a time, a noise such as an induced voltage due to the ignition spark produced at the spark plug installed in another cylinder is applied to the control electrode of the associated semiconductor switching element and thereby renders it conductive, it will result in the ignition of the improper spark plug and hence a deterioration of the engine performance quality.

SUMMARY OF THE INVENTION

It is an object of the present invention to provide an improved ignition system in which during the normal running of an internal combustion engine, the charging of the capacitors by the unwanted charging half waves generated in the capacitor charging coil is practically prevented, thereby preventing the undesired charging of the capacitors and hence the occurrence of erroneous ignition.

It is another object of the present invention to provide an improved ignition system in which if the engine is rotated in an improper direction, the generation of the ignition sparks which would cause the engine to continue rotating in the improper direction is prevented.

It is still another object of the present invention to provide an improved ignition system in which an improved ignition advance characteristic is obtained at

the time of ignition as the number of revolutions of the engine is increased.

It is still another object of the present invention to provide an improved ignition system in which the developed voltage on the capacitors during the intermediate and high speed operation of the engine can be made uniform without increasing the number of charging cores considerably.

It is still another object of the present invention to provide an improved ignition system which is simple in construction yet capable of positively stopping the engine.

It is still another object of the present invention to provide an improved ignition system for two-cylinder engines which comprises capacitor charging coils each generating three cycles of its output voltage for each rotation of the engine.

The present invention thus comprises an improved capacitor discharge type contactless ignition system for internal combustion engines in which any misoperation of the engine may be prevented to ensure reliable operation thereof, since the undesired storage action of the capacitors are prevented, since an improved ignition advance characteristic is ensured and since the development of uniform charging voltage for the capacitors is facilitated.

BRIEF DESCRIPTION OF THE DRAWING

FIGS. 1, 2, 3, 7, 8, 9, 10, 12, 13, 15, 16, 17, 19, 22, 25, 27, 28, 31 34, 37, 41, 43, 46 and 20 are electric wiring diagrams of 1st to 23rd embodiments and 13th embodiment of this invention, respectively;

FIGS. 4, 14, 21, 26, 30, 32, 35, 38, 42 and 47 are waveform diagrams for explaining the operation of the embodiments;

FIGS. 5A and 5B show respectively the external revolving type four-pole magneto generator and timing generator employed in the embodiment shown in FIG. 1, with FIG. 5A showing a cross-sectional view taken along the line VA—VA of FIG. 5B and FIG. 5B showing a cross-sectional view taken along the line VB—VB of FIG. 5A;

FIGS. 6A and 6B are perspective views showing two forms of the stator of the magneto generator employed in the embodiment of FIG. 3;

FIG. 11 is an ignition advance characteristic diagram for the embodiments shown in FIGS. 1, 2, 3, 7, 8, 9 and 10;

FIG. 18 is a cross-sectional view of the external revolving type six-pole magneto generator and timing generator employed in the embodiment shown in FIG. 13;

FIGS. 23A, 23B and 23C show the internal revolving type six-pole magneto-generator and timing generators employed in the embodiment of FIG. 15, with FIG. 23A showing a cross-sectional view taken along the line XXIIIA — XXIIIA of FIG. 23B, FIG. 23B showing an enlarged cross-sectional view taken along the line XXIIIB — XXIIIB of FIG. 23A and FIG. 23C showing a plan view of the timing generators with part in section;

FIG. 24 is a plan view showing part in section a modified form of the timing generators shown in FIG. 23C;

FIGS. 29A and 29B show the external revolving type six-pole magneto generator and timing generators employed in the embodiment shown in FIG. 28, with FIG. 29A showing a cross-sectional view of the generators

and FIG. 29B showing a cross-sectional view taken along the line XXIXB — XXIXB of FIG. 29A;

FIG. 33 is a plan view showing part in section a schematic plan view of the timing generator employed in the embodiment shown in FIG. 31;

FIGS. 36A and 36B show the external revolving type eight-pole magneto generator employed in the embodiment shown in FIG. 34, with FIG. 36A showing a cross-sectional view of the magneto generator and FIG. 36B showing a perspective view of the principal part of the generator;

FIG. 39 is an electric circuit diagram showing a modified form of the switching element employed in the system of this invention;

FIG. 40 is an electric circuit diagram showing a modified connection of the cancellation signal generating means employed in the system of this invention;

FIG. 44 is a cross-sectional view of the external revolving type four-pole magneto generator and timing generator employed in the embodiments shown in FIGS. 41 and 43;

FIGS 45A and 45B show respectively a perspective view and plan view of the stator employed in the magneto generator shown in FIG. 44;

FIG. 48 is an electric circuit diagram showing the short-circuit switching element employed in the embodiment shown in FIG. 46;

FIG. 49 is a waveform diagram for explaining the operation of the embodiment of FIG. 2 in which the ignition timing for the forward running of the engine is deviated from that for the reverse running to prevent the engine from operating in the reverse direction;

FIG. 50 is an electric circuit diagram showing another modified form of the connection of the ignition control means and the cancellation signal generating means employed in the system of this invention;

FIG. 51 is an electric circuit diagram showing still another modified form of the ignition control means employed in the system of this invention;

FIG. 52 is an electric circuit diagram showing still another modified form of the connection of the cancellation signal generating means employed in the system of this invention; and

FIG. 53 is an electric circuit diagram showing a modified connection of the arc duration extending diodes employed in the system of this invention.

DESCRIPTION OF THE PREFERRED EMBODIMENTS

The preferred embodiments of the present invention will now be explained. The first embodiment shown in FIG. 1 will be described first. In FIG. 1, numerals 1 and 2 designate the capacitor charging coils of a four-pole magneto generator, 3 and 4 rectifying diodes, 5 and 6 capacitors, 7 and 8 diodes, 9 and 10 ignition coils, 9a and 10a the respective ignition coil primary windings, 9b and 10b the respective ignition coil secondary windings. Numerals 11 and 12 designate spark plugs provided for the respective cylinders of an internal combustion engine, 13 and 14 thyristors constituting semiconductor switching elements, 15, 16 and 17 transformers consisting of current transformers having respectively primary windings 15a, 16a and 17a and secondary windings 15b, 16b and 17b, 18, 19, 20 and 21 diodes, 22 a timing generator synchronized with the above-mentioned magneto generator, 48a and 48b the generating coils of the timing generator. Numerals 23

and 24 designate diodes, 25 a self-restoring switch, 28 a diode which absorbs the induced electromotive force of the current transformer 15 and which prevents the discharging current of the capacitor 5 from flowing into the current transformer 15.

The construction of the above-mentioned magneto generator and timing generator will be described with references to FIGS. 5A and 5B, in which numeral 30 designates a rotor comprising an iron shell 31, four permanent magnets 32a, 32b, 32c and 32d spaced apart at equal intervals and securely embedded in the inner side of the iron shell 31 by means of a nonmagnetic material 31a such as aluminum or resin, pole pieces 33a, 33b, 33c and 33d secured respectively to the inner face of the permanent magnets 32a, 32b, 32c and 32d, a center piece 34 securely mounted on a crankshaft 34a of the engine by a nut 34b and securely fixing the iron shell 31 by means of rivets which are not shown and a timing core 35 of the timing generator 22 secured to the center piece 34. Numeral 40 designates a stator secured to the engine, 41 and 42 capacitor charging cores placed one upon another and securely mounted on the stator 40 at the same place thereon with the above-mentioned capacitor charging coils 1 and 2 being wound respectively on the cores 41 and 42. Numeral 43 designates a lamp load core securely mounted on the stator 40 at a position displaced by about 180°, i.e., opposite to the capacitor charging cores 41 and 42, with a lamp load power supply coil 44 constituting a power supply for a load such as lamps. Numeral 22a designates the stator of the timing generator 22 securely mounted on the stator 40 at a position displaced by about 90° from the capacitor charging cores 41 and 42, the stator 22a comprising a permanent magnet 46, cores 47a and 47b disposed on the opposite sides of the magnet 46, generating coils 48a and 48b wound respectively on the cores 47a and 47b and connected in series with each other, a case 49 in which the said elements are housed and a sealing resin 45 filled in the case 49.

With the magneto generator constructed as above described, for each revolution of the magneto generator, i.e., for each rotation of the engine crankshaft 34a, the capacitor charging coils 1 and 2 generate two cycles of the AC no-load voltage as shown in FIG. 4(a), while, for each rotation of the crankshaft 34a, the timing generator 22 generates one cycle of the no-load output voltage as shown by the solid line in FIG. 4 (g) at the time when the positive half wave of the second cycle of the capacitor charging coils 1 and 2 is generated.

The operation of the first embodiment constructed as described above will now be explained. The operation of the various parts of the embodiment which take place along with the rotation of the engine will be explained with reference to FIG. 4 showing the waveforms produced at various points of the system. When the generated voltage of the capacitor charging coils 1 and 2 begins to increase in the position direction at a time t_1 in FIG. 4, the current shown by the solid line in FIG. 4(b) flows through the circuit comprising the capacitor charging coil 1, the rectifying diode 3, the primary winding 15a of the transformer 15, the capacitor 5 and the parallel circuit consisting of the diode 7 and the primary winding 9a of the ignition coil 9. This current produces the output shown in FIG. 4(c) in the secondary winding 15b of the transformer 15 so that the thyristor 14 is driven into conduction and thus the ca-

pacitor charging coil 2 is shortcircuited through the thyristor 14 to thereby make the charging of the capacitor 6 by the capacitor charging coil 2 ineffective. And the capacitor 5 is charged to develop thereacross the terminal voltage shown in FIG. 4(e). Thereafter, as the generated voltage of the capacitor charging coils 1 and 2 begins to increase in the negative direction at a time t_2 , the current shown by the broken line in FIG. 4(b) flows through the circuit comprising the capacitor charging coil 1, the ground, the primary winding 16a of the transformer 16, the diode 18 and the capacitor charging coil 1 and the circuit comprising the capacitor charging coil 2, the ground, the primary winding 17a of the transformer 17, the diode 19 and the capacitor charging coil 2, so that the current shown by the solid line in FIG. 4(d) flows through the secondary winding 16b of the transformer 16 and the secondary winding 17b of the transformer 17, respectively. This current causes the thyristors 13 and 14 to conduct at a time t_3 , whereby the charge stored in the capacitor 5 is discharged through the circuit comprising the thyristor 13, the ground, the primary winding 9a of the ignition coil 9, the capacitor 5 and the diode 28, thereby producing a high voltage in the secondary winding 9b of the ignition coil 9 and producing an ignition spark at the spark plug 11.

Here, the purpose of the diode 7 is to keep the current flowing through the primary winding 9a of the ignition coil 9 to extend the arc duration of the ignition spark. In this case, if the thyristor 14 is caused to conduct, no ignition spark is produced at the spark plug 12 since there is no charge stored in the capacitor 6.

Then, at a time t_4 , the output of the timing generator 22 synchronized with the rotation of the magneto generator is produced as shown by the solid line in FIG. 4(g) and thereafter when this output causes the thyristor 13 to conduct at the same time when the generated voltage of the capacitor charging coils 1 and 2 changes from the negative to positive direction, the generated voltage of the capacitor charging coil 1 is short-circuited by the thyristor 13. On the other hand, the generated voltage of the capacitor charging coil 2 is supplied through the circuit comprising the rectifying diode 4, the capacitor 6 and the parallel circuit consisting of the diode 8 and the primary winding 10a of the ignition coil 10 and the ground, thereby charging the capacitor 6 as shown in FIG. 4(f). Then, when the generated voltage of the capacitor charging coils 1 and 2 changes from the positive to negative direction, in the same manner as at the previous time, the current shown by the solid line in FIG. 4(d) flows in each of the secondary windings of the transformers 16 and 17, so that the thyristors 13 and 14 are caused to conduct at a time t_5 and thus the charge stored in the capacitor 6 is discharged through the circuit comprising the thyristor 14, the ground, the primary winding 10a of the ignition coil 10 and the capacitor 6, producing an ignition spark at the spark plug 12. When this occurs, the system reverts to the initial condition and the above-described process of operations is repeated to alternately produce an ignition spark at the spark plugs 11 and 12. In this first embodiment, the engine stopping circuit is such that the capacitor charging side terminals of the capacitor charging coils 1 and 2 are interconnected directly through the switch 25 so that when one of the capacitor charging coils charges its associated capacitor, the other capacitor charging coil is short-circuited. Ac-

cordingly, by closing the switch 25, both of the capacitor charging coils 1 and 2 may be short-circuited and thus the charging of the capacitors 5 and 6 may be prevented, thereby stopping the rotation of the engine.

FIG. 2 illustrates the second embodiment of the present invention. The second embodiment differs from the first embodiment in that the transformer 15 is replaced with a timing generator 22' having generating coils 48a' and 48b' for producing the output as shown by the one-dot-chain lines in FIG. 4(g). The timing generator 22' comprises the previously mentioned timing core 35 shown by the solid line in FIG. 5B and a stator 22a' mounted on the stator 40 at a position diametrically opposite to the stator 22a of the timing generator 22 as shown by the two-dot-chain line. If either one of the two sets of the circuits shown on both sides of the one-dot-chain line is employed alone, this embodiment may be used as an ignition system for single-cylinder engines.

FIG. 3 illustrates the third embodiment of the present invention. In this embodiment, the ignition system according to this invention comprises two high-speed capacitor charging coils 1a and 2a each having a relatively low number of turns, two low-speed capacitor charging coils 1b and 2b each having a relatively high number of turns, and diodes 54 and 55 which are connected in parallel with the low-speed capacitor charging coils 1b and 2b, whereby the high-speed capacitor charging coil 1a is connected in series with the low-speed capacitor charging coil 1b and the high-speed capacitor charging coil 2a is connected in series with the low-speed capacitor charging coil 2b, and the series connected capacitor charging coils 1a and 1b and the capacitor charging coils 2a and 2b are respectively wound on the capacitor charging cores 41 and 42 placed one upon the other at the same position on the stator 40 as shown in FIG. 6A. Further, in FIG. 3, numerals 56 and 57 designate resistors, 58 and 59 semiconductor elements (e.g., thermistors) having a negative resistance characteristic which prevent the output of the transformers 16 and 17 from changing with temperature changes.

The third embodiment constructed as above described operates in the following manner. When the engine is operating at a low speed, the generated output of all the capacitor charging coils 1a, 1b, 2a and 2b are low. However, because of a relatively small delay in the generated voltage of the low-speed capacitor charging coils 1b and 2b due to the impedances of the capacitor charging coils 1a, 1b, 2a and 2b by their inductances as well as the short-circuiting of the reverse voltages by the diodes 54 and 55, the output of the series connected two capacitor charging coils 1a and 1b (or 2a and 2b) sufficiently charges the capacitor 5 (or 6). On the other hand, during the high speed operation of the engine, there is a relatively large delay in the generated voltage of the low-speed capacitor charging coils 1b and 2b due to the impedances of the low-speed capacitor charging coils 1b and 2b by their inductances and the short-circuiting of the reverse voltages by the diode 54 and 55, practically all the output of the high-speed capacitor charging coils 1a and 2a with which the diodes 54 and 55 are not connected in parallel flow to the capacitors 5 and 6 through the diodes 54 and 55, thereby charging the capacitors 5 and 6. Here, the impedance of the capacitor charging coils 1a, 1b, 2a and 2b increases in proportion to the square of the number

of turns in the respective coils and in proportion to increase in the number of revolutions of the engine and therefore, during the high speed operation of the engine, the internal voltage drop of the respective capacitor charging coils 1a, 1b, 2a and 2b increases with resultant drop in the capacitor charging voltage. With the diodes 54 and 55 connected in parallel with the low-speed capacitor charging coils 1b and 2b of the series connected capacitor charging coils 1a, 1b and 2a, 2b, during the high speed operation, the capacitor 5 (or 6) is charged only with the output of the high-speed capacitor charging coil 1a (or 2a) through the diode 54 (or 55) as mentioned previously. Consequently, while the no-load voltage produced in the high-speed capacitor charging coil 1a (or 2a) decreases in proportion to the number of turns as compared with the case where the two capacitor charging coils 1a and 1b (or 2a and 2b) are connected in series, its impedance decreases in proportion to the square of the number of turns, and moreover the generated voltage of the capacitor charging coils generally increases in proportion to increase in the engine revolutions. Therefore, the voltage on the capacitor 5 (or 6) during the high speed operation can be ultimately increased. Consequently, the voltage on the capacitors 5 and 6 can be made uniform during the intermediate and high speed operation of the engine.

Further, since the series connected capacitor charging coils 1a and 1b, and 2a and 2b are separately wound on the different capacitor charging cores 41 and 42, particularly during the high speed operation of the engine, the counter magnetomotive forces produced by the low-speed capacitor charging coils 1b and 2b having the diodes 54 and 55 connected in parallel therewith largely reduce the magnetic flux passing through the capacitor charging cores 41 and 42. However, since the high-speed capacitor charging coils 1a and 2a for charging the capacitors 5 and 6 are wound respectively on separate ones of the capacitor charging cores 41 and 42, and since the capacitor charging cores 41 and 42 having wound thereon the high-speed capacitor charging coils 1a and 2a for charging the capacitors 5 and 6 are also provided with the low-speed capacitor charging coils 1b and 2b wound thereon so that during the charging operation of the high-speed capacitor charging coil 1a or 2a, the low-speed capacitor charging coil 1b or 2b associated with the other cylinder is short-circuited by the thyristor 13 or 14 always producing a substantially constant counter magnetomotive force independently of the number of revolutions of the engine, the voltage on the capacitors 5 and 6 during the intermediate and high speed operation of the engine can be made more uniform.

In this embodiment, instead of the stacked structure of the capacitor charging cores 41 and 42, the cores 41 and 42 may be arranged side by side as shown in FIG. 6B.

FIG. 7 illustrates the fourth embodiment of the present invention which differs from the first embodiment of FIG. 1 in that instead of applying the output of the transformer 15 to the gate electrode of the thyristor 14, the capacitor charging coil 1 is provided with a center tap so that a portion of the output of the capacitor charging coil 1 is applied to the gate electrode of the thyristor 14 through the center tap 1c, resistor 26 and diode 24.

FIG. 8 illustrates the fifth embodiment of the present invention. In this embodiment, thyristors 13' and 14'

for making the capacitor charging half waves of the capacitor charging coils 1 and 2 ineffective are connected respectively across the terminals of the capacitor charging coils 1 and 2 so that the charge stored in the respective capacitors 5 and 6 are discharged respectively through the primary windings of ignition coils 9 and 10 by means of the thyristor 13 controlled by the output of the transformer 16. In FIG. 8, numerals 13a and 13b designate diodes. Also this embodiment may be adapted for use with single-cylinder engines by utilizing only those circuits which are shown on the upper side of the one-dot-chain line in FIG. 8.

FIG. 9 illustrates the sixth embodiment of the present invention in which the thyristors 13' and 14' for making the capacitor charging half waves from the capacitor charging coils 1 and 2 ineffective are connected respectively across the terminals of the capacitors 5 and 6. This embodiment may also be adapted for use with single-cylinder engines by utilizing only those circuits which are shown on the upper side of the one-dot-chain line in FIG. 9.

Further, in the fifth and sixth embodiments, as shown by the broken lines in FIGS. 8 and 9, the primary winding 17a of the transformer 17 may be connected across the terminals of the capacitor charging coil 2 through the diode 19 and the secondary winding 17b of the transformer 17 may be connected to the gate electrode of the thyristor 13 so that the thyristor 13 may be controlled by the output of the transformers 16 and 17, respectively. In this way, the circuit constants of the charging circuit for the capacitor 5 may be made equal to those of the charging circuit for the capacitor 6, thereby eliminating any unbalance between the voltages on the capacitors 5 and 6 and lack of symmetry in the ignition timing.

FIG. 10 illustrates the seventh embodiment of the present invention. This embodiment differs from the first embodiment of FIG. 1 in that in place of the transformer 15 and the diode 28, a diode 50 is connected in series with the primary winding 9a of the ignition coil 9 and the gate circuit of the thyristor 14 is inserted in the charging circuit for the capacitor 5. The operation of this embodiment is substantially the same with that of the first embodiment. Further, in this seventh embodiment, the ignition control means for the thyristors 13 and 14 comprises the single transformer 16 and both of the thyristors 13 and 14 can be controlled with the output from the secondary side of the transformer 16.

It will be thus seen that in the first through seventh embodiments so far described, the ignition control means for discharging the capacitors 5 and 6 comprises one or both of the transformers 16 and 17 each composed of a current transformer. Thus, as the number of revolutions of the engine increases, the output current value increases as shown by the broken line in FIG. 4(d) and therefore the time of conduction of the thyristors 13 and 14 is advanced. On the other hand, when a high engine speed is attained, the amount of increase in the output current value of the transformers 16 and 17 decreases due to the magnetic saturation of the transformer cores and the inductances of the windings 16a, 16b, 17a and 17b and the time of conduction of the thyristors 13 and 14 becomes substantially constant. Consequently, the relationship between the number N of revolutions of the engine and the ignition timing of the spark plugs 11 and 12 becomes as shown in FIG. 1, providing an excellent ignition advance charac-

teristic. A similar ignition advance characteristic may also be obtained by employing potential transformers in place of the current transformers constituting the transformers 16 and 17 and by turning the thyristors 13 and 14 on with the output of these potential transformers.

Further, in addition to the ignition control means employed in the above-mentioned first to seventh embodiments, the output of the timing generator 22 may also be used for this purpose as used in the eighth embodiment shown in FIG. 12. In other words, as shown by the two-dot-chain line in FIG. 5B, a second timing core 35a is provided on the center piece 34 at a position leading the timing core 35 by about 90°, whereby the timing generator 22 generates output signals as shown by the solid and broken lines in FIG. 4(g) and the timing generator 22' generates output signals as shown by the one-dot-chain line and two-dot-chain line in FIG. 4(g), thereby causing the thyristors 13 and 14 to conduct in response to these outputs so as to discharge the capacitor 5 without using the transformer 16 or the like. In this eighth embodiment, the series connected high-speed capacitor charging coil 1a(2a) and low speed capacitor charging coil 1b(2b) are wound on the same capacitor charging core and the diode 54(55) is connected in parallel with the low-speed capacitor charging coil 1b(2b). In this way, the voltage on each of the capacitors 5 and 6 is made uniform during the intermediate and high speed operation of the engine. This embodiment may also be adapted for use with single cylinder engines by employing one of the two sets of circuits shown on the upper and lower sides of the one-dot-chain line in FIG. 12.

Further, while, in the first to eighth embodiments described above, the magneto generator of the four-pole type is employed, multipole magneto generators having more than four poles, e.g., the six-pole and eight-pole types may also be employed. For example, in the ninth embodiment shown in FIG. 13, the ignition system employing a six-pole magneto generator is used in the operation of a two-cylinder engine. FIG. 14 shows the waveforms generated at various points in this system. The capacitor charging coils 1 and 2 generate respectively three cycles of the oppositely phased output voltages for each revolution of the magneto generator as shown in FIGS. 14(a₁) and 14(a₂), respectively, and the timing generator 22 generates, as shown by the solid lines in FIG. 14(b), two outputs at 180° intervals to make ineffective one each of the capacitor charging half waves from the capacitor charging coils 1 and 2. The capacitors 5 and 6 then discharge as shown by the solid line in FIGS. 14(c₁) and 14(c₂), respectively, so that the secondary outputs of the transformers 16 and 17 are generated as shown in FIGS. 14(d₁) and 14(d₂), respectively, alternately generating at these instants an ignition spark at the spark plugs 11 and 12, while the secondary outputs of the transformers 15 and 57 are generated as shown by the solid line in FIGS. 14(e₁) and 14(e₂), respectively, to make ineffective the remaining capacitor charging half wave from the capacitor charging coils 1 and 2, respectively. In FIG. 13, numerals 57a and 57b designate respectively the primary and secondary windings of the transformer 57, 58 a diode provided to serve the similar purpose as the diode 28, 23a, 23b, 24a and 24b diodes.

FIG. 15 illustrates the tenth embodiment of the present invention which differs from the ninth embodiment

of FIG. 13 in that the timing generators 22 and 22' are connected respectively to the gate electrode of the thyristors 13 and 14 and that the primary windings 15a and 57a of the transformers 15 and 57 are connected respectively between the capacitor 5 and the primary winding 9a of the ignition coil 9 and between the capacitor 6 and the primary winding 10a of the ignition coil 10.

Further, the ninth and tenth embodiments may be so adapted that the capacitors 5 and 6 are charged by two half wave outputs of the capacitor charging coils 1 and 2 and thereafter the timing generators 22 and 22' generate the output voltages shown by the one-dot-chain lines in FIG. 14(b) to produce the required ignition sparks at the spark plugs 11 and 12.

FIG. 16 illustrates the eleventh embodiment of this embodiment. This embodiment differs from the tenth embodiment of FIG. 15 in that the transformers 15 and 57 are replaced with transformers 59 and 60 connected respectively in parallel with the ignition coils 9 and 10, whereby the remaining one each of the capacitor charging half waves from the capacitor charging coils 1 and 2 are made ineffective by the secondary outputs of the transformer 59 and 60 generated as shown by the broken lines in FIGS. 14(e₁) and 14(e₂). In FIG. 16, numerals 59a and 60a designate respectively the primary windings of the transformers 59 and 60, 59b and 60b the secondary windings of the transformers 59 and 60.

FIG. 17 illustrates the eleventh embodiment of this invention, which differs from the tenth embodiment of FIG. 15 in that the thyristors 13 and 14 are connected respectively in series with the primary windings 9a and 10a of the ignition coils 9 and 10, and the primary windings 9a and 10a of the ignition coils 9 and 10 are connected respectively in parallel with the respective charging circuits for the capacitors 5 and 6.

FIG. 18 illustrates the construction of the six-pole magneto generator employed in the above-described ninth of eleventh embodiments, which comprises six permanent magnets 32a, 32b, 32c, 32d, 32e and 32f which are secured in the inner face of an iron shell 31a at equal intervals, and six pole pieces 33a, 33b, 33c, 33d, 33e and 33f which are secured respectively to the inner faces of the six permanent magnets.

FIG. 19 illustrates the thirteenth embodiment of this invention in which the capacitors 5 and 6 are alternately charged with the positive and negative to half waves of the single capacitor charging coil 1, and the discharging of the charge stored in the capacitors 5 and 6 and the cancellation of the unwanted charging half waves from the capacitor charging coil 1 are simultaneously effected by the single signal voltage from the timing generator 22. In operation, the capacitor charging coil 1 generates the no-load-voltage shown in FIG. 21(a) so that when the voltage begins to increase in the direction of the solid line arrow (positive direction) at a time t_1 , current flows through the circuit comprising the capacitor charging coil 1, diode 3, primary winding 15a of transformer 15, capacitor 5, the parallel circuit of diode 7 and primary winding 9a of ignition coil 9, the ground and diode 19, thereby charging the capacitor 5 as shown by the solid line in FIG. 21(f). In this case, the output shown in FIG. 21(c) is produced in the secondary winding 15b of the transformer 15 so that when the generated voltage of the capacitor charging coil 1 is about to change from the positive to negative direction, the output voltage of the transformer 15 causes the thy-

istor 14 to conduct and thus the voltage in the direction of the broken line arrow (negative direction) in FIG. 19 is short-circuited through the circuit comprising the capacitor charging coil 1, diode 4, thyristor 14, the ground and diode 18. Then, at a time t_2 when the generated voltage of the capacitor charging coil 1 changes to the direction of the solid line arrow (positive direction) in FIG. 19, the output voltage of the timing generator 22 shown in FIG. 21(e) causes the thyristors 13 and 14 to conduct so that the charge stored in the capacitor 5 is discharged through the circuit comprising the capacitor 5, diode 28, thyristor 13, the ground and the primary winding 9a of ignition coil 9, thereby inducing a high voltage in the secondary winding 9b of the ignition coil 9 and thus producing an ignition spark at the spark plug 11.

In this case, the generated voltage of the capacitor charging coil 1 in the direction of the solid line arrow (positive direction) in FIG. 21(a) is short-circuited by the thyristor 13. On the other hand, though the thyristor 14 is simultaneously driven into conduction, there is no charge stored in the capacitor 6 and therefore no ignition spark is produced.

Then, at a time t_3 , the voltage in the direction of the broken arrow line (negative direction) in FIG. 19 occurs, so that the capacitor 6 is charged as shown by the solid line in FIG. 21(g) through the circuit comprising the capacitor charging coil 1, diode 4, primary winding 57a of transformer 57, capacitor 6, the parallel circuit of diode 8 and primary winding 10a of ignition coil 10 and the ground, and the output of the secondary winding 57b of the transformer 57 produced at this time causes the thyristor 13 to conduct to thereby short-circuit the next positive going half wave of the capacitor charging coil 1. Thereafter, the thyristors 13 and 14 are driven into conduction by the output voltage of the timing generator 22 generated at a time t_4 as shown in FIG. 21(e) and thus the charge stored in the capacitor 6 is discharged through the circuit comprising the capacitor 6, diode 58, thyristor 14, the ground, and primary winding 10a of ignition coil 10, thereby producing an ignition spark at the spark plug 12. Repetitions of the above-described operations alternately produce an ignition spark at the spark plugs 11 and 12.

FIG. 20 illustrates another embodiment of the present invention. This embodiment differs from the thirteenth embodiment of FIG. 19 in that there are provided two timing generators 22 and 22' and two capacitor charging coils 1 and 2 for generating the oppositely phase output voltages shown in FIGS. 21(a) and 21(b), respectively, whereby the thyristors 13 and 14 are placed in a conductive state by the signals from the separate timing generators 22 and 22'.

In this embodiment, the circuitry of the previously described eighth embodiment of FIG. 12 may be employed so as to control the thyristors 13 and 14 with only the output of the timing generators 22 and 22'. In other words, the generated signals of the timing generators 22 and 22' may be provided as shown in FIGS. 21(h) and 21(i) one for every two positive outputs of the series connected capacitor charging coils 1a, 1b and 2a, 2b shown in FIGS. 21(a) and 21(b), thereby charging the capacitors 5 and 6 as shown by the solid lines in FIGS. 21(f) and 21(g), respectively. Alternately, the capacitors 5 and 6 may be charged respectively in two steps, as shown by the broken lines in FIGS. 21(f) and 21(g), by two positive going outputs

of the series connected capacitor charging coils 1a, 1b and 2a, 2b shown in FIGS. 21(a) and 21(b), and thereafter the timing generators 22 and 22' may be caused to generate the second one of the two consecutive signals shown in FIGS. 21(h) and 21(i), respectively, for the third positive going output of the series connected capacitor charging coils 1a, 1b and 2a, 2b, respectively, after the initiation of the charging operation thereof. This embodiment may also be adapted for use with single-cylinder engines by employing either one of the two sets of the circuits shown on the upper and lower sides of the one-dot-chain line in FIG. 12.

FIG. 22 illustrates the fourteenth embodiment of this invention. This embodiment differs from the embodiment of FIG. 20 in that in place of the transformers 15 and 57 and the diodes 28 and 58, diodes 50 and 51 are connected respectively in series with the primary windings 9a and 10a of the ignition coils 9 and 10 and the gate and cathode of the thyristors 13 and 14 are connected respectively in the charging circuits for the capacitors 5 and 6 whereby the charging current for the capacitors 5 and 6 are used as the gating signals for the thyristors 13 and 14 and that the capacitor charging coils 1 and 2 are provided respectively with center taps 1c and 2c to divide the capacitor charging coils 1 and 2 into the high-speed coil portions 1a' and 2a' and low-speed coil portions 1b' and 2b', and diodes 54 and 55 are connected respectively in parallel with the low-speed coil portions 1b' and 2b', thereby making uniform the voltage on the capacitors 5 and 6 during the intermediate and high speed operation of the engine.

Further, with the previously described circuitry shown in FIGS. 2 and 12, respectively, and applied to a four-pole magneto generator, if the polarity of the output voltage of the capacitor charging coils 1a and 1b and of the capacitor charging coils 2a and 2b are reversed with respect to each other and if the position of the timing cores of the timing generators 22 and 22' are selected so that their output waveforms are generated at given points, it is possible to provide an ignition system for two-cylinder engines with a six-pole magneto generator.

Furthermore, if a four-pole magneto generator is employed, there is only one charging half wave for the capacitors 5 and 6 which is not used. Therefore, if this must be cancelled simultaneously with the occurrence of ignition as mentioned earlier, it is necessary for the timing generators 22 and 22' to generate only one cycle of their respective output voltages for providing the required ignition sparks for one operation during one revolution of the crankshaft.

Further, the six-pole magneto generator employed in the above-described embodiments may consist of the internal revolving type illustrated in FIGS. 23A, 23B and 23C. The construction of this type of magneto generator will now be explained with reference to FIGS. 23A, 23B and 23C, in which numeral 30' designates a rotor comprising a nonmagnetic material 31a' consisting of aluminum, resin etc., a ring-shaped permanent magnet 32' having at regular intervals six projecting poles 32a', 32b', 32c', 32d', 32e' and 32f', a pole piece member 33' having six pole pieces arranged respectively on the outer surface of the projecting poles 32a', 32b', 32c', 32d', 32e' and 32f' of the permanent magnet 32', and a center piece 34' securely mounted on an engine crankshaft 34a by a bolt 34b'. The center piece 34' is

fit on the inner surface of the permanent magnet 32' and both of them are securely embedded in the non-magnetic material 3140. Numeral 40 designates a ring-shaped yoke having two capacitor charging cores 41' and 42' and four lamp load cores 43a', 43b', 43c' and 43d' which are integrally formed on the inner surface of the yoke 40 at equal intervals to project therefrom. The previously mentioned capacitor charging coils 1 and 2 are wound respectively on the capacitor charging cores 41' and 42' so that the capacitor charging coils 1 and 2 generate three cycles of the 180° symmetrical no-load AC voltage as shown by the solid lines in FIGS. 14(a₁) and 14(a₂). The four lamp load cores 43a', 43b', 43c' and 43d' have respectively wound thercon lamp load power supply coils 44a, 44b, 44c and 44d constituting the power supplies for the lamps which are not shown. Numeral 40b' designates the engine housing to which the yoke 40' is secured and numeral 40c' designates the magnet generator housing.

Numerals 22b and 22b' designate the stators of the previously mentioned timing generators 22 and 22', which are securely mounted on the housing 40c' at positions diametrically opposite to each other, the stators comprising two juxtaposed cores 47a' and 47b', a yoke 48' securely holding the cores 47a' and 47b', the previously mentioned generating coils 48a and 48b or 48a' and 48b' which are mounted respectively on the cores 47a' and 47b' and a sealing resin 45' for sealing and insulating the above-mentioned component elements. Numeral 35' designates the rotor for the timing generators 22 and 22' which comprises an axially magnetized ring permanent magnet 46', disk yokes 47c' and 47d' disposed respectively on the upper and lower sides of the permanent magnet 46', a ring-shaped nonmagnetic material 31b of aluminum, resin, etc., which is disposed on the outer periphery of the permanent magnet 46' and interposed between the yokes 47c' and 47d', a plurality of rivets 49' for securely holding the yokes 47c' and 47d' together and the center piece 34c' securely fit onto the inner periphery of the permanent magnet 46'. The center piece 34c' securely mounted, along with the previously mentioned center piece 34', on the engine crankshaft 34a by the bolt 34b'. The yoke 47c' is also provided with two pawls 50a and 50b integrally formed therewith and spaced away from each other by a certain distance to oppose to the cores 47a' and 47b' of the stators 22b and 22b'. The pawls 50a and 50b form south poles. The yoke 47d' also has a pawl 50c integrally formed therewith to oppose to the cores 47a' and 47b' of the stators 22b and 22b' and positioned between the pawls 50a and 50b. The pawl 50c forms the north pole. For each rotation of the crankshaft 34a, the timing generator 22 generates the output voltage shown by the solid line in FIG. 14(g), while the timing generator 22' generates one cycle of the output voltage shown by the broken line in FIG. 14(b) for each revolution of the crankshaft 34a.

Further, in the magneto generator of the type described above, a rotor 35a' as shown in FIG. 24 may be used with the timing generators 22 and 22'. This rotor 35a' comprises circumferentially magnetized two permanent magnets 46a' and 46b', magnetic poles 50a', 50b' and 50c' having one ends thereof respectively positioned on the sides and between the permanent magnets 46a' and 46b' and the other ends opposed to the cores 47a' and 47b' of the stators 22b and 22b', and a nonmagnetic material 31c' of

aluminum, resin, etc., in which these magnets and poles are embedded.

Further, if the internal revolving type magneto generator as shown in FIGS. 23(a), 23(b) and 23(c) is used in an application where the timing generators 22 and 22' are required to generate two cycles of the output voltages as shown by the solid lines in FIG. 14(b) and FIG. 21(e), respectively, an additional set of pawls similar to the pawls 50a, 50b and 50c may be provided at suitable positions of the rotor 35' for the timing generators 22 and 22'. On the other hand, if the timing generators 22 and 22' as shown in FIG. 24 are employed, an additional set of permanent magnets and pawls similar to the permanent magnets 46a' and 46b' and the pawls 50a', 50b' and 50c' may be provided at suitable positions of the rotor 35a'.

FIG. 25 illustrates the fifteenth embodiment of the present invention in which the ignition system employing a six pole magneto generator is used in the operation of a three-cylinder engine. The waveforms generated at various points in this system are shown in FIG. 26. Three capacitor charging coils 1, 2 and 2' generate respectively three cycles of the output voltage as shown in FIG. 26(a). Three timing generators 22, 22' and 22'' generate their respective outputs as shown in FIGS. 26(b₁), 26(b₂) and 26(b₃), thereby respectively making ineffective two of the capacitor charging half waves of the capacitor charging coils 1, 2 and 2'. Three capacitors 5, 6 and 6' charge and discharge as shown in FIGS. 26(c₁), 26(c₂) and 26(c₃) to sequentially produce an ignition spark at three spark plugs 11, 12 and 12'. FIG. 26(d) shows the secondary output of the transformer 16, which causes the three capacitors 5, 6 and 6' to discharge in sequence. In FIG. 25, numeral 4' designates a rectifying diode, 8' a diode, 10' an ignition coil having a primary winding 10a' and a secondary winding 10b', 14' a thyristor, 18a, 18b, 20b, 23c, 24c diodes.

FIG. 27 illustrates the sixteenth embodiment of this invention, which differs from the fifteenth embodiment of FIG. 25 in that the transformer 15 is provided in the capacitor charging circuit in place of the timing generator 22''.

FIG. 28 illustrates the seventeenth embodiment of the invention in which the required cancellation signal generating means are provided by the timing generators 22, 22' and 22'' which are provided separately for the respective cylinders. As shown in FIG. 29A, stators 22a, 22a' and 22a'' of the timing generators 22, 22' and 22'', respectively, are provided at 120° intervals on the stator 40 to the outside of a bell-shape flywheel main body 31 in opposition of the flywheel main body 31. The bell-shape flywheel main body 31 is provided with three timing cores 35a, 35b and 35c. Further, as shown in FIG. 29B, the timing generators 22, 22' and 22'' are provided respectively with signal coils 48c, 48c' and 48c'' which are wound respectively on the outer periphery of cores 47a'' disposed in opposition to the timing cores 35a, 35b and 35c, with one end face of the core 47a'' connected to a magnet 46'' and the other end face of the magnet 46'' connected to another L-shaped core 47b''. These component elements are enclosed with a nonmagnetic material 45'' of aluminum, resin, etc., the forward ends of the L-shaped cores 47b'' are opposed to the outer peripheral surface of the flywheel main body 31 so that the signal coils 48c, 48c' and 48c'' respectively generate at predetermined points three cycles of the output voltage as shown in

FIGS. 30(d), 30(e) and 30(f) for each revolution of the engine. Further, as shown in FIG. 29A, the three capacitor charging cores 41, 42 and 43 are mounted on the stator 40 at equal intervals and capacitor charging coils 1, 2 and 2' are wound respectively on the cores 41, 42 and 43, whereby the capacitor charging coils 1, 2 and 2' generate respectively the voltage waveforms shown in FIGS. 30(a), 30(b) and 30(c).

With the construction described above, the seventeenth embodiment of this invention operates in the following manner. When, at a time T_1 , the timing cores 35b and 35c cause the signal coils 48c' and 48c'' of the timing generators 22' and 22'' to generate the voltages shown in FIGS. 30(e) and 30(f), thyristors 14 and 14' are placed in a conductive state thereby short-circuiting the capacitor charging coils 2 and 2'. And the generated voltage of the capacitor charging coil 1 causes a current flow through the circuit comprising the diode 3, the capacitor 5, the parallel circuit consisting of the diode 7 and the primary winding 9a of the ignition 9 and the ground, charging the capacitor 5 to the voltage shown by the broken line in FIG. 30(a). Then, when the generated voltages of the capacitor charging coils 1, 2 and 2'' change to the direction opposite to the capacitor charging direction, a short-circuit current flows through the capacitor charging coil 1, the ground, the primary winding 16a of the transformer 16 and the diode 18. At a low engine speed, the generated voltage is low and hence the output voltage of the secondary winding 16b of the transformer 16 is low. Thus, at a time T_2 in FIG. 30, the thyristor 13 is not placed in a conductive state. Then, at a time T_3 , the timing core 35a causes the signal coil 48c of the stator 22a of the timing generator 22 to generate the voltage shown in FIG. 30(d), whereby the thyristor 13 is driven into conduction and thus the charge stored in the capacitor 5 is discharged through the circuit comprising the thyristor 13, the ground and the primary winding 9a of the ignition coil 9, including a high voltage in the secondary winding 9b of the ignition coil 9 and thereby producing an ignition spark at the spark plug 11. When the engine speed reaches a predetermined number of revolutions, a sufficiently large output voltage is generated from the secondary winding 16b of the transformer 16 and consequently the thyristor 13 is driven into conduction at the time T_2 as shown by the two-dot-chain line in FIG. 30(a). As a result, a step advance of the ignition timing from the time T_3 to T_2 is effected providing a better engine operation. In this case, while, at the time T_2 , the signals are simultaneously applied to the other thyristors 14 and 14' in addition to the thyristor 13, there is no charge previously stored in the capacitors 6 and 6' and therefore no ignition sparks are produced at the spark plugs 12 and 12'.

When, at a time T_4 , the timing cores 35b and 35c come into alignment with the stators 22b and 22a' of the timing generators 22 and 22'', the signal coils 48c and 48c'' generate signal voltages so that the generated voltages of the capacitor charging coils 1 and 2' are simultaneously short-circuited by the thyristors 13 and 14'. Then, the generated voltage of the capacitor charging coil 2 causes a current flow through the circuit comprising the coil 2, the diode 4, the capacitor 6, the parallel circuit consisting of the diode 8 and the primary winding 10a of the ignition coil 10, thereby charging the capacitor 6 to the voltage shown by the broken

line in FIG. 30(b). On the other hand, at the low engine speed, the thyristor 14 is driven into conduction at a time T_6 by the output voltage from the signal coil 48c' of the stator 22a' of the timing generator 22', whereas at the intermediate and high engine speed, the thyristor 14 is driven into conduction at the time T_5 by the secondary output voltage of the transformer 17, producing a high voltage in the secondary winding 10b of the ignition coil 10 and thereby providing an ignition spark at the spark plug 12.

Similarly, the capacitor 6' commences to charge at a time T_7 as shown by the broken line in FIG. 30(c) and the capacitor charging coils 1 and 2 are short-circuited by the signal voltages of the timing generators 22 and 22' through the thyristors 13 and 14. Then, at a time T_8 (for the intermediate and high speed operation) or T_9 (for the low speed operation), an ignition spark is produced at the spark plug 12'.

Then, at a time $T_{10} = T_1$, the thyristors 14 and 14' are driven into conduction by the signal voltages of the timing generators 22' and 22'' and thus the capacitor charging coils 2 and 2' are short-circuited.

In the manner described above, the required ignition sparks are sequentially produced at the spark plugs 11, 12 and 12' at 120° intervals.

In the case of an internal combustion engine which requires no step advance, the circuit arrangement of the eighteenth embodiment shown in FIG. 31 may be used. In this arrangement, the timing core 35a used in the arrangement of FIG. 29 may be eliminated. The operating voltage waveform for this arrangement is as shown in FIG. 32. Further, the timing generators may be constructed as shown in FIG. 33. In the construction shown in FIG. 33, a rotor 35b' which is secured to a crankshaft 34a, comprises a permanent magnet 46'', cores 50a'' and 50b'' disposed on both sides of the permanent magnet 46' and a nonmagnetic material 31c'' enclosing these elements and formed into a disk shape. Each of timing generator stators 22b, 22b' and 22b'' comprises a C-shaped core 47a'' and they also comprise respectively signal coils 48a and 48b, 48a' and 48b', and 48a'' and 48b'' which are wound on the respective cores 47a''. These signal coils are grouped into pairs each comprising the two coils wound on the different cores and connected in series. In other words, the signal coil 48a is connected in series with the signal coil 48b', the signal coil 48a' with the signal coil 48b'' and the signal coil 48a'' with the signal coil 48b. The series connected signal coils 48a and 48b', 48a' and 48b'', and 48a'' and 48b are connected respectively to the thyristors 13, 14 and 14' at their respective gate electrodes.

FIG. 34 illustrates the nineteenth embodiment of this invention. In this embodiment, the high-speed capacitor charging coil 1a and the low-speed capacitor charging coil 1b of a eight pole magneto generator which produce outputs of same phase, are connected in series and the diode 54 is connected in parallel with the low-speed capacitor charging coil 1b, whereby the voltage on the capacitors during the intermediate and high-speed operation of the engine is made uniform and at the same time the thyristors 13 and 14 are alternately driven into conduction by the generated voltages of the timing generators 22 and 22' in association with the charging of the capacitor 5, whereby the charge on the capacitor 5 is discharged alternately through the primary windings 9a and 10a of the ignition coils 9 and 10.

The waveforms generated at various points in this system are shown in FIG. 35. The solid line in FIG. 35(a) indicates the generated voltage of the capacitor charging coils 1a and 1b and the broken line indicates the voltage to which the capacitor 5 is charged. FIGS. 35(b) and 35(c) show the generated voltages of the timing generators 22 and 22'.

The construction of the magneto generator employed in this embodiment is as shown in FIGS. 36A and 36B. In this construction, eight pole pieces 33a, 33b, 33c, 33d, 33e, 33f, 33g and 33h as well as eight permanent magnets 32a, 32b, 32c, 32d, 32e, 32f, 32g and 32h which are magnetized normal to the axial direction, are mounted on the inner surface of a bell flywheel body portion 31. The pole pieces 33a to 33h are secured to the flywheel main body 31 through the intermediary of the permanent magnets 32a to 32h. Numerals 64a, 64b and 64c designate the auxiliary poles of the timing generators 22 and 22' which are projected adjacent those portions of the flywheel main body 31 where the permanent magnets 32g and 32h are secured, and numerals 65a and 65b designate the auxiliary poles for the timing generators 22 and 22' which are projected respectively from the pole pieces 33g and 33h. The auxiliary poles 64a, 64b and 64c which are provided on the flywheel main body 31 and the auxiliary poles 65a and 65b which are projected from the pole pieces 33g and 33h are alternately arranged. Numerals 22c and 22c' designate the stators of the timing generators 22 and 22' which are mounted on the stator 40 at diametrically symmetrical positions and which comprise respectively signal coils 48c and 48c''. The cores 47a''' are positioned to oppose the auxiliary poles 64a, 64b, 64c, 65a and 65b. Numeral 47b''' designates the respective iron cases magnetically shielding the signal coils 48c and 48c''. Numerals 43a and 43b designate lamp load power supply coils wound respectively on lamp load power supply cores 44a and 44b. The charging cores 41 and 42 are securely mounted on the stator 40 at the diametrically opposed positions and so are the lamp load power supply cores 44a and 44b. Both the capacitor charging coils 1a and 1b and the lamp load power supply coils 43a and 44a are positioned to oppose the pole pieces 33a, 33b, 33c, 33d, 33e, 33f, 33g and 33h.

When the engine crankshaft rotates, the pole pieces 33a to 33h generate an interlinkage flux through the capacitor charging coils 1a and 1b and the lamp load power supply coils 43a and 43b, producing an AC voltage in the capacitor charging coils 1a and 1b and the lamp load power supply coils 43a and 43b. On the other hand, the respective auxiliary poles 65a and 65b provided on the two pole pieces 33g and 33h and the respective auxiliary poles 64a, 64b and 64c provided on the bell flywheel main body 31 create an interlinking flux through the signal coils 48c and 48c'' and the displacement of this flux generates in the signal coils 48c and 48c' a plurality of cycles of the continuous wave output shown in FIGS. 35(b) and 35(c), respectively. By generating, in this way, a plurality of continuous output voltages in each of the timing generators, a plurality of gating signals can be applied to the thyristors 13 and 14, respectively, thereby positively controlling the thyristors 13 and 14. This applies equally to not only the embodiments so far described, but also other embodiments which will be described later.

FIG. 37 illustrates the twentieth embodiment of the present invention. In the ignition system of this embodiment

employing an eight-pole magneto generator, thyristor 13' and 14' are connected respectively across the terminals of the capacitor charging coils 1 and 2 and the thyristors 13 and 14 are respectively driven into conduction by the secondary outputs of transformers 15 and 57 provided in the capacitor charging circuits whereby the charge on the capacitors 5 and 6 are discharged respectively through the primary windings 9a and 10a of the ignition coils 9 and 10, while the capacitors 5 and 6 are charged respectively by the two-peak charging half wave outputs of the capacitor charging coils 1 and 2. The waveforms generated at various points in this system are shown in FIG. 38. In FIG. 38, the solid lines in FIGS. 38(a) and 38(b) show the generated voltages of the capacitor charging coils 1 and 2 and the broken lines show the voltages to which the capacitors 5 and 6 are charged. The solid lines in FIGS. 38(c) and 38(d) show the generated voltages of the timing generators 22 and 22' and FIGS. 38(e) and 38(f) show the output voltages of the transformers 15 and 57.

Further, in the circuit constructions shown in FIGS. 2, 3, 8, 9, 12, 25, 28, 31 and 37, the timing generators 22 and 22' (or 22, 22' and 22'') may be caused to generate signal voltages as shown by the solid lines in FIG. 4(h), 26(e), 30(g), 32(g) and 38(g) just prior to the generation of half wave outputs for charging the capacitors 5 and 6 (or 5, 6 and 6') in the capacitor charging coils 1 and 2 (or 1a, 1b, 2a and 2b or 1, 2 and 2') to thereby prevent the engine from operating in the reverse direction. In other words, when the rotation of the engine is reversed, the polarity of the generated voltage of the capacitor charging coil (1, 1a, 1b, 2, 2a, 2b, 2') and the timing generator (22, 22', 22'') is reversed with respect to that of the corresponding waveforms shown in all of the above-mentioned waveform diagrams. Accordingly, if the thyristor (13, 14, 14') is driven into conduction by the outputs of the timing generator (22, 22', 22'') at the instant when the generated voltage of the capacitor charging coil (1, 1a, 1b, 2, 2a, 2b, 2') rises to that direction which charges the capacitor (5, 6, 6'), the charging of the capacitor (5, 6 and 6') by the capacitor charging coil (1, 1a, 1b, 2, 2a, 2b, 2') may be made ineffective as shown by the two-dot-chain lines in FIGS. 30(a), (b) and (c), FIGS. 32(a), (b) and (c) and FIGS. 38(a), (b) and (c). In this way, when the rotation of the engine is reversed, the charging of the capacitor (5, 6, 6') by the capacitor charging coil (1, 1a, 1b, 2, 2a, 2b, 2') may be practically prevented, thereby ensuring positive prevention of the engine from reversing its direction of rotation without the breaking down of any component elements. Further, even if the voltage proof of the thyristor (13, 14, 14') is deteriorated, there is no danger of an ignition spark occurring at an incorrect instant as was the case in the past, since practically no charge is stored in the capacitor (5, 6, 6') when the engine is rotated in the reverse direction, and therefore more positive prevention of the engine from reversing its direction of rotation can be ensured.

Furthermore, since no ignition spark occurs when the engine rotates in the reverse direction and since an independent ignition method is employed to make ineffective all the unwanted charging half waves of the capacitor charging coil (1, 1a, 1b, 2, 2a, 2b, 2') when the engine is rotating in the proper direction, the effectiveness of the system of this invention is more perfect. In

other words, in a simultaneous ignition method in which two spark plugs are connected to a single ignition coil so as to simultaneously ignite two cylinders, if the starter switch is closed to start the engine or the engine is started by a kick forcegetting the fact that the stop switch has been previously closed, or if, while driving, the stop switch is closed to rotate the engine by inertia, the drive will eventually notice that the engine is not operating and in such a case it is not infrequent that the driver turns off the stop switch and tries to restart the engine. When this occurs, particularly in the case of a two-cylinder internal combustion engine, there is the danger that a rich mixture previously supplied into the cylinders will be ignited by the ignition sparks which occur near the bottom dead center and this flame will be emitted through the exhaust pipe causing a fire. This is the same when the rotation of the engine is reversed. Consequently, the safety of operation of internal combustion engines, particularly two-cycle engines can be improved with the independent ignition type system of this invention in which the ignition coils (9, 10, 10') are connected respectively to the spark plugs (11, 12, 12') so that the ignition sparks occur only in the vicinity of the top dead center during the forward running of the engine and which is further adapted to prevent the occurrence of any ignition sparks when the engine is rotated in the reverse direction.

Further, in order to have the timing generators 22 and 22' generate the signal voltages shown by the solid lines in FIG. 4(h), two timing cores 35b and 35c may be mounted on the center piece 34 at a position just before the timing core 35a and at another position diametrically opposite to that position, respectively, as shown by the one-dot-chain lines in FIG. 5B. Further, in order that the timing generators 22 and 22' may generate the signal voltages shown by the solid lines in FIGS. 30(h) and 32(g), respectively, it is necessary only to mount three timing cores 35d, 35e and 35f on the bell flywheel main body 31, respectively, just before the timing cores 35b and 35c in FIG. 29A and at a position 120° apart from said two positions.

On the other hand, in the arrangements shown in FIGS. 15, 16, 17, 20 and 22 in which the capacitor charging coils 1 and 2 generate voltages of opposite polarity, the timing generators 22 and 22' may be adapted to generate their respective signal voltages as shown by the solid lines in FIGS. 14(f₁) and 14(f₂) just before the capacitor charging coils 1 and 2 generate their respective half wave outputs for charging the capacitors 5 and 6, thereby preventing the engine from reversing its direction of rotation. In this case, as shown by the two-dot-chain lines in FIG. 18, three timing cores 35a, 35b and 35c may be mounted on the center piece 34 at a position just before the timing core 35 and before and behind that position displaced by 120° therefrom, respectively, thereby causing the timing generators 22 and 22' to generate the output voltages shown by the solid lines in FIGS. 14(f₁) and 14(f₂). Further, with the internal revolving type magneto generator shown in FIGS. 23A, 23B and 23C, the rotor 35' of the timing generators 22 and 22' may be similarly provided with additional pawls at proper positions thereon, thereby causing the generators 22 and 22' to generate the output voltages shown by the solid lines in FIGS. 14(f₁) and 14(f₂).

Further, in the arrangements shown in FIGS. 2, 3, 8,

9, 12, 25, 28, 31 and 37 in which the cancellation signal generating means comprise the timing generators 22 and 22', as for example, the sense of connection of the signal coils 48a, 48b, 48a' and 48b' of the timing generators 22 and 22' may be reversed or the polarity of the permanent magnet 46 may be reversed so that, as shown by the broken lines in FIGS. 14(f₁) and 14(f₂), the timing generators 22 and 22' generate their respective negative going half waves just prior to the generation by the capacitor charging coil (1, 1a, 2, 2a) of the unwanted charging half waves for the capacitors 5 and 6 and positive half waves immediately after the generation of such unwanted charging half waves. In this way, the timing generators 22 and 22' are required to generate only one cycle of their outputs, that is, if the external revolving type magneto generator shown in FIG. 18 is employed, both of the two timing cores successively mounted on the center piece 34 may, with only one timing core mounted therebetween, short-circuit the unwanted half waves of the generated voltages of the capacitor charging coils (1, 1a, 2, 2a) for charging the capacitors 5 and 6 and thereby prevent the engine from reversing its direction of rotation. Further, in the arrangement in which the timing generators 22, 22' and 22'' generate the signal voltages as shown by the solid lines in FIGS. 14(f₁) and 14(f₂), while there is the danger that depending on the choice of ignition advance characteristic and timing of the output voltages of the timing generators 22, 22' and 22'', at design, any delay 25 in the output voltage of the transformers 16, 17 and 17' at the low engine speeds may cause the discharging time of the capacitors 5, 6 and 6' by these outputs to overlap the time at which the output voltages of the timing generators 22, 22' and 22'' are applied to the thyristors 13, 14 and 14' thereby deteriorating the ignition advance characteristic at the low engine speeds, the generation of the output voltages shown by the solid lines in FIGS. 14(f₂) by the timing generators 22, 22' and 22'' has the effect so that while the output voltages of the transformers 16, 17 and 17' are on during the forward running of the engine, the timing generators 22, 22' and 22'' generate no half wave output voltages which turn on the thyristors 13, 14 and 14', thereby providing an excellent ignition advance characteristic even at the low engine speeds. Further, if the engine is rotated in the reverse direction, the thyristors 13, 14 and 14' will be caused to conduct at the instant when the generated voltages of the capacitor charging coils 1, 2 and 2' rise in the direction which charges the capacitors 5, 6 and 6', thereby reducing the charge stored in the capacitors 5, 6 and 6'.
 Further, in the circuit constructions shown in FIGS. 2, 3, 8, 9, 12, 25, 28, 31 and 37, the practically the same effect as above-mentioned may be obtained by replacing the thyristors 13, 13', 14, and 14' with bi-directional thyristors 13a, 13a', 14a and 14a' such as shown in FIG. 39 and causing the timing generators 22, 22' and 22'' to generate the output voltages at the points of the broken lines in FIGS. 14(f₁) and 14(f₂) and FIG. 30(g) or alternately the output voltages of opposite polarity with respect to the broken line voltages. In this case, the connections of the signal coils (48a, 48', 48a'', 48b, 48b', 48b'') of the timing generators 22, 22' and 22'' with these bi-directional thyristors can be made in either way and thus there is no danger of any error in the connections.
 Further, the similar result can be obtained without

using the bi-directional thyristors 13a, 13a', 14a and 14a', if the output voltages of the signal coils (48a, 48a', 48a'', 48b, 48b', 48b'') of the timing generators 22, 22' and 22'' are applied to the thyristors (13, 13', 14, 14') after being subjected to full-wave rectification by full-wave rectifiers 71, 72 and 72' as shown in FIG. 40.

Further, in the arrangements shown in FIGS. 12, 31 and 34 in which all the required control signals for the thyristors (13, 14, 14') are generated from the timing generators (22, 22', 22''), referring to the case represented by waveform diagram of FIG. 4, when the engine is operating in the proper direction, the thyristors 13 and 14 may be driven into conduction by the positive going half wave voltages shown by the solid lines in FIG. 4(h) so that the charge stored in the capacitors 5 and 6 are discharged respectively through the primary windings 9a and 10a of the ignition coils 9 and 10 thus producing ignition sparks at the spark plugs 11 and 12, whereas when the engine is operated in the reverse direction, the thyristors 13 and 14 are caused to conduct by the half waves of opposite polarity with respect to the solid line voltage in FIG. 4(h) (polarity reversal occurs when the engine reverses its direction of rotation) so that the charging of the capacitors 5 and 6 by the capacitor charging coils 1 and 2 may be made ineffective. In other words, with the single timing core and one cycle of the output voltages of the timing generators 22 and 22', the dual functions of effecting the ignition and preventing the engine from reversing its direction of rotation can be achieved.

Still further, in the circuit construction shown in FIG. 34 in which the timing generators 22 and 22' are required to generate a plurality of continuous signals as shown in FIGS. 35(b) and 35(c), respectively, it is possible to mount auxiliary poles 64a, 64b and 64c on the bell flywheel main body 31 near the permanent magnet 32f and also mount auxiliary poles 65a and 65b on the pole piece 33f as shown by the two-dot-chain lines in FIG. 36A, whereby the timing generators 22 and 22' generate a plurality of continuous signals as shown in FIGS. 35(d) and 35(e), respectively, and thus the charging of the capacitor 5 by the capacitor charging coils 1a and 1b upon reversal of the direction of rotation of the engine can be made ineffective to thereby prevent the continued operation of the engine in the reverse direction.

FIG. 41 illustrates the twenty first embodiment of the present invention in which the high-speed capacitor charging coil 1a and the low-speed capacitor coil 1b are connected in parallel with each other through diodes 3a and 3b. The generated voltage waveforms of the timing generator 22 are as shown by the solid and broken lines in FIG. 42(d), while the generated voltage waveforms of the capacitor charging coils 1a and 1b are as shown in FIGS. 42(a) and 42(b) with the phase of the generated voltage of the high-speed capacitor charging coil 1a leading the generated voltage of the low-speed capacitor charging coil 1b by 60° which is less than 180°. When, at a time T₁ in FIG. 42, the generated voltage of the high-speed capacitor charging coil 1a rises to the direction which charges the capacitor 5, the capacitor 5 is charged through the circuit comprising the high-speed capacitor charging coil 1a, the diode 3a, the parallel circuit consisting of the diode 7 and the primary winding 9a of the ignition coil 9 and the ground. Then, at a time T₂, the generated voltage of the low-

speed capacitor charging coil 1b charges the capacitor 5 in the similar manner through the diode 3b. Consequently, the capacitor 5 is charged as shown by the broken in FIG. 42(a). Then, at a time T₃, the voltage shown in FIG. 42(d) is generated in the timing generator 22 and this voltage is applied to the gate electrode of the thyristor 13 through the diode 23 thereby rendering the thyristor 13 conductive. When this occurs, the charge stored in the capacitor 5 is discharged rapidly through the circuit comprising the thyristor 13, the ground and the primary winding 9a of the ignition coil 9, inducing a high voltage in the secondary winding 9b of the ignition coil 9 and thereby producing an ignition spark at the spark plug 11. Thereafter, at a time T₅, the voltage shown by the solid line in FIG. 42(d) is generated in the timing generator 22 so that the second cycle of the generated voltage of the high-speed capacitor charging coil 1a is short-circuited by the conduction of the thyristor 13 thereby making the charging of the capacitor 5 ineffective. In this case, the conduction through the thyristor 13 is sustained while the generated voltage of the high-speed capacitor charging coil 1a remains on in the direction which charges the capacitor 5. Consequently, when, at a time T_{5'}, the generated voltage of the low-speed capacitor charging coil 1b rises to the direction which charges the capacitor 5, this voltage is simultaneously short-circuited by the thyristor 13 making the charging of the capacitor 5 ineffective. In this way, one ignition spark is produced at the spark plug 11 for each rotation of the crankshaft during the forward running of the engine. Further, in this embodiment, the low-speed capacitor charging coil 1b has a high number of turns and a large inductance with the result that the rise of the generated voltage of the low-speed capacitor charging coil 1b is gradually retarded as the number of revolutions of the engine increases. However, since the thyristor 13 remains in a conductive state while the generated voltage of the high-speed capacitor charging coil 1a remains on in the direction which charges the capacitor 5, the unwanted capacitor charging half waves of the low-speed capacitor charging coil 1b can be positively made ineffective.

On the other hand, when the rotation of the engine is reversed, the thyristor 13 is rendered conductive by the output voltages (opposite polarity) of the timing generator 22 which are shown respectively by the solid line at a time T_{5''} and the broken line at a time T_{1'} in FIG. 42(d), thereby short-circuiting the generated voltage of the low-speed capacitor charging coil 1b for charging the capacitor 5 through the thyristor 13. Then, the voltage generated in the high-speed capacitor 1a in the direction to charge the capacitor 5 while the generated voltage of the low-speed capacitor charging coil 1b for charging the capacitor remains on, is also short-circuited by the thyristor 13. In this way, no charging of the capacitor 5 takes place when the engine is rotated in the reverse direction.

FIG. 43 illustrates the twenty second embodiment of this invention in which the output voltage of the transformer 16 connected across the terminals of the high-speed capacitor charging coil 1a is utilized to control the ignition timing and to make ineffective the charging of the capacitor 5 by the capacitor charging coils 1a and 1b when the rotation of the engine is reversed. When the engine is operating in the proper direction, the output voltage shown by the solid line in FIG. 42(c) is generated from the transformer 16 so that the thy-

istor 13 is rendered conductive at the time T_3 and thus the stored charge on the capacitor 5 is discharged through the primary winding 9a of the ignition coil 9. On the other hand, when the rotation of the engine is reversed, the output voltage shown by the one-dot-chain lines in FIG. 42 (c) is generated from the transformer 16, whereby the thyristor 13 is turned on at the times T_2 and T_5 thus short-circuiting the voltage for charging the capacitor 5 generated in the low-speed capacitor charging coil 1b. And the voltage generated by the high-speed capacitor charging coil 1a in the direction to charge the capacitor 5 while the voltage of the low-speed capacitor charging coil 1b for charging the capacitor 5 is on, is also short-circuited by the thyristor 13.

FIG. 44 illustrates one form of the magneto generator employed in the twenty first and twenty second embodiments described above. As will be seen from FIG. 44, in the magneto generator of the four-pole type, the capacitor charging cores 41 and 42 and the load power supply core 43 are mounted on the stator 40 at 120° intervals and capacitor charging coils 1a and 1b and the lamp load power supply coil 44 are wound respectively on the cores 41, 42 and 43, whereby the output voltage waveform shown by the solid lines in FIGS. 42(a) and 42(b) are generated in the capacitor charging coils 1a and 1b.

In another form of the magneto generator, as shown in FIGS. 45A and 45B, the charging cores 41 and 42 respectively having the capacitor charging coils 1a and 1b wound thereon may be placed one on top of another so that the charging core 41 with the high-speed capacitor charging coil 1a is out of alignment with the charging coil 42 with the low-speed capacitor charging coil 1b to produce a phase lead of 60 electrical degrees, thereby causing the capacitor charging coils 1a and 1b to generate the output voltage waveforms shown by the solid lines in FIGS. 42(a) and 42(b).

FIG. 46 illustrates the twenty third embodiment of this embodiment in which a short-circuit thyristor 75 is connected between the gate and cathode of the thyristors 13 and 14 and the gate electrode of the thyristor 75 is connected to a gating signal generating coil 1d provided in the magneto generator in the similar manner as the capacitor charging coils 1a and 1b. In FIG. 46, numerals 76, 77, 78 and 79 designate diodes. In this twenty third embodiment, when the rotation of the engine is reversed, the output of the gating signal generating coil 1d is applied to the thyristor 75 connected between the gate and cathode of the thyristors 13 and 14, whereby the output voltages of the timing generators 22 and 22' are short-circuited through the thyristor 75, rendering the thyristors 13 and 14 inoperative and thereby preventing the engine from operating in the reverse direction. The waveforms generated in various points in this embodiment are shown in FIGS. 47(a) through 47(e). In FIGS. 47 (a) and 47(d), the solid lines show the generated voltages of the capacitor charging coils 1a and 1b in the magneto generator and the broken lines show the voltages to which the capacitors 5 and 6 are charged. FIGS. 47(b) and 47(e) show the generated voltages of the timing generators 22 and 22' and FIG. 47(c) shows the generated voltage of the gating signal generating coil 1d in the magneto generator. In other words, since the timing generators 22 and 22' also perform the function of making ineffective the unwanted half waves of the generated voltages of the

capacitor charging coils 1a and 1b for charging the capacitors 5 and 6, two cycles of their signal voltages are generated at predetermined points for each revolution of the crankshaft. On the other hand, the gating signal generating coil 1d generates the output voltage whose phase lags the output voltages of the capacitor charging coils 1a and 1b by predetermined degrees to thereby make ineffective all the positive going half wave output voltages of the timing generators 22 and 22' when the rotation of the engine is reversed. While, in this twenty third embodiment, the thyristor 75 is used to short-circuit between the gate and cathode of the thyristors 13 and 14, a transistor 75' may be employed in place of the thyristor 75 to shortcircuit between the gate and cathode of the thyristors 13 and 14.

In addition to the above-described arrangements for preventing the engine from operating in the reverse direction, the same effect can be obtained by introducing a large difference between the ignition timing for the engine operating in the proper direction and that used when the rotation of the engine is reversed. The latter arrangement will be explained referring, by way of example, to the circuit construction shown in FIG. 2 and the waveform diagram of FIG. 49. When the engine is rotating in the proper direction, the timing generators 22 and 22' generate the output voltages shown by the solid lines in FIGS. 49(c) and 49(d) and the transformers 16 and 17 generate their outputs later than the output voltages of the timing generators 22 and 22' generated at times T_2 and T_5 in FIG. 49. In other words, when the engine is rotating in the proper direction, the ignition sparks are produced at the spark plugs 11 and 12 by the output voltages of the timing generators 22 and 22' generated at the times T_2 and T_5 in FIG. 49 and consequently the output voltages of the transformers 16 and 17 occur after the capacitors 5 and 6 have been discharged, thus producing no ignition sparks.

On the other hand, when the engine starts to rotate in the reverse direction for some reason, a polarity reversal occurs for the generated voltages of the capacity charging coils 1 and 2 so that, starting at a time T_1' , the capacitor 5 is charged with the generated voltage of the capacitor charging coil 1 as shown by the one-dot-chain line in FIG. 49(a), while the generated voltage of the capacitor charging coil 2 is short-circuited through the conduction of the thyristor 14 by the signals [the broken lines in FIG. 49(d)] of the timing generators 22 and 22'. Assuming now that the transformers 16 and 17 are not present, the charge stored in the capacitor 5 by the capacitor charging coil 1 from the time T_1' is discharged as shown by the two-dot-chain line in FIG. 49(a) through the thyristor 13 upon its conduction by the signal of the timing generator 22 generated at a time T_4' as shown by the broken line in FIG. 49(c), thereby igniting the engine. In this case, the ignition point occurs at a rather advanced point in the compression stroke of the engine and there is thus the danger of the engine continuing its rotation in the reverse direction. However, with the provision of the transformers 16 and 17, the stored charge on the capacitor 5 is discharged by the output signal of the transformer 16 generated as shown by the one-dot-chain line in FIG. 49(e) at a time T_2' by the oppositely phase voltage of the capacitor charging coil 1, thereby effecting the ignition. Thus, the difference in ignition point between the forward running and the reverse running amounts to $\theta' \approx 160^\circ$ as compared with $\theta \approx 90^\circ$ obtained when the

transformer 16 is not present. This ignition point occurs in the compression stroke of the engine and moreover at a point very close to the bottom dead center. Therefore, no sufficient power is produced and there is high-speed no danger of the engine continuing to rotate in the reverse direction.

Here, the additional single peak charging voltage generated in the capacitor charging coil 1 at the time T_4 is short-circuited by the signal voltage [the broken line in FIG. 49(c)] of the timing generator 22 generated at the time T_4 . Further, similarly with the capacitor charging coil 1, the capacitor charging coil 2 charges the capacitor 6 as shown by the one-dot-chain line in FIG. 49(b), whereby the stored charge is discharged as shown by the one-dot-chain line in FIG. 49(b) by the output of the transformer 17 shown by the one-dot-chain line in FIG. 49(e) and consequently an ignition spark occurs at a point displaced by about 160° from the ignition time used when the rotation of the engine is reversed.

Further, in the above-described embodiments of this invention wherein the transformers (16, 17, 17') and the timing generators (22, 22', 22'') are connected respectively to the gate electrodes of the thyristors (13, 14, 14'), the timing generators (22, 22', 22'') may be connected respectively in series with the secondary windings (16b, 17b, 17b') of the transformer (16, 17, 17') as shown in FIG. 50.

Furthermore, in the above-described embodiments wherein the transformer (16, 17, 17') are connected respectively across the terminals of the capacitor charging coils (1, 1a, 1b, 2, 2a, 2b, 2'), a phase inverter circuit 98 comprising, as shown in FIG. 51, resistors 91, 92, 93 and 94, a Zener diode 95, a thyristor 96 and a capacitor 97 may be employed in place of the transformer (16, 17, 17'). With this phase inverter circuit 98, when, following the half wave for charging the capacitor (5, 6, 6'), the next half wave of opposite polarity is generated in the capacitor charging coil (1, 1a, 1b, 2, 2a, 2b, 2'), current flows through the circuit comprising the resistor 94, the capacitor 97, the resistor 93 and the diode 18 (19, 19'), charging the capacitor 97 in the polarity shown. Then, when the generated voltage of the capacitor charging coil (1, 1a, 1b, 2, 2a, 2b, 2') becomes higher than the Zener voltage of the Zener diode 95, the Zener diode 95 is rendered conductive and thus the thyristor 96 is turned on, discharging the stored charge on the capacitor 97 through the gate and cathode of the thyristor (13, 14, 14'), the thyristor 96 and the resistor 93 and thereby rendering the thyristor (13, 14, 14') conductive. In this way, the stored charge on the capacitor (5, 6, 6') is discharged, inducing a high voltage in the secondary winding (9b, 10b, 10b') of the ignition coil (9, 10, 10') and thereby providing an ignition spark at the spark plug (11, 12, 12'). Even with the phase inverter circuits 98, an excellent ignition advance characteristic can be obtained as is the case when the transformers, e.g., current or voltage transformers are used.

Further, in the embodiments wherein the generated outputs of the capacitor charging coils 1 and 2 are of 180° opposite polarity as in the case of an ignition system for two-cylinder engines employing a six-pole magneto generator, as shown in FIG. 52, a thyristor 13' may be connected through diodes 13a' and 13b' across the terminals of the capacitor charging coils 1 and 2 so that the thyristor 13' is turned on by the output voltage

of the cancellation signal generating means, e.g., the timing generator 22, 22', etc. thereby making the charging of the capacitors 5 and 6 by the unwanted capacitor charging half waves of the capacitor charging coils 1 and 2 substantially ineffective.

Further, while, in the above-described embodiments of this invention, the diodes 7, 8 and 8' are connected respectively across the terminals of the primary windings 9a, 10a and 10a' of the ignition coils 9, 10 and 10' for the purpose of ensuring a longer arc duration time for the spark plugs 11, 12 and 12', as shown in FIG. 53, the diode 7 (8, 8') may be connected in inverse parallel relation across the terminals of the thyristor 13 (14, 14') so that a closed circuit is completed by the capacitor 5 (6, 6'), the diode 7 (8, 8') and the primary winding 9a (10a, 10a') of the ignition coil 9 (10, 10'). Consequently, upon the conduction of the thyristors 13 (14, 14') the charge on the capacitor 5 (6, 6') is discharged by way of the circuit comprising the thyristor 13 (14, 14') and the primary winding 9a (10a, 10a') of the ignition coil 9 (10, 10') thereby charging the capacitor 5 (6, 6') in the opposite polarity. This charge of opposite polarity is then redischarged through the circuit comprising the primary winding 9a (10a, 10a') of the ignition coil 9 (10, 10') and the diode 7 (8, 8'). In this way, the capacitor 5 (6, 6') may be alternately caused to charge and discharge by the stored charge on the capacitor 5 (6, 6') so that current is continuously supplied alternately from both positive and negative directions into the primary winding 9a (10a, 10a') of the ignition coil 9 (10, 10') to thereby ensure a longer arc duration time for the spark plug 11 (12, 12').

I claim:

1. In a capacitor discharge type contactless ignition system for an internal combustion engine, used with a magneto generator, comprising:

charging circuit means including capacitor charging coil means coupled to a magneto generator for generating an alternating current signal during rotation of said magneto generator, rectifying means for rectifying said alternating current signal of said capacitor charging coil means to produce halfwaves and a capacitor, said coil means rectifying means and capacitor being connected in series to permit current flow from said capacitor charging coil means through said rectifying means and said capacitor,

discharging circuit means connected to said capacitor including semiconductor switching means having a control electrode and a primary winding of an ignition coil having said primary winding and a secondary winding, said capacitor switching means and primary winding being connected in series to cause the stored charge on said capacitor to discharge through said primary winding upon conduction of said switching means;

a spark plug connected to said secondary winding; and

ignition control means connected to said control electrode of said semiconductor switching means for sequentially generating ignition timing signals in synchronism with the rotation of an engine, the time between adjacent timing signals defining a cycle and including a plurality of half-waves, the improvement comprising:

bypassing conduction means connected to said

charging circuit means for preventing charging of said capacitor; and bypassing controlling means for causing said alternating current to by-pass said capacitor through said bypassing conduction means, when said engine is rotating in a normal direction, for all but a selected number less than all of half-waves of said alternating current signal, which will otherwise charge said capacitor, and which are produced by said capacitor charging coil means after said ignition timing signal during each cycle, said cycle having a duration from a certain ignition timing signal to the next ignition timing signal and starting from the point where said capacitor begins charging.

2. An ignition system as set forth in claim 1, wherein said ignition control means is a transformer connected to said capacitor charging coil means.

3. An ignition system as set forth in claim 1 wherein said ignition control means includes a timing signal generator having signal coil means coupled to said magneto generator for producing a sequence of ignition signals during rotation of said magneto generator; and inductor means, mounted in said magneto generator for inducing said ignition timing signal in said signal coil means.

4. An ignition system as set forth in claim 3, wherein said bypass controlling means includes

second inductor means mounted in said magneto generator for inducing in said signal coil means a control signal.

5. An ignition system as set forth in claim 1 wherein said bypassing conduction means includes means for connecting said semiconductor switching means to said bypass controlling means so that for each cycle all but one of said half-waves are passed through said switching means.

6. An ignition system as set forth in claim 5, wherein said switching means is connected across both terminals of said capacitor charging coil means.

7. An ignition system as set forth in claim 1 wherein said bypassing conduction means is connected in parallel with said capacitor.

8. An ignition system as set forth in claim 1 wherein said capacitor charging coil means comprises two coils wound on different cores mounted in said magneto generator.

9. An ignition system as set forth in claim 1, wherein said capacitor charging coil means generates at least three cycles of said alternating current for each revolution of said magneto generator, and said capacitor is charged with more than two half-waves of said alternating current.

10. An ignition system as set forth in claim 1 wherein said capacitor charging coil means comprises two coils connected in parallel and out of phase by less than 180 degrees with each other.

11. An ignition system as set forth in claim 1, further comprising:

a second charging circuit means including a second capacitor charging coil means for generating alternating current;

a second rectifying means for rectifying said alternating current of said second capacitor charging coil means and second capacitor, said second coil means, second rectifying means and second capacitor being connected in series to permit current flow from said capacitor charging coil means through

said second rectifying means and said second capacitor;

a second discharging circuit means connected to said second capacitor, including second semiconductor switching means having a control electrode and a primary winding of a second ignition coil having said primary winding and a secondary winding said second switching means second primary winding and second capacitor being connected in series to cause the stored charge on said second capacitor to discharge through said second primary winding upon conduction of said second switching means; a second spark plug connected to said secondary winding;

a second ignition control means connected to said control electrode of said second semiconductor switching means of said second discharging circuit means for generating ignition timing signals in synchronism with the rotation of said engine, the time between adjacent signals defining a cycle and including a plurality of halfwaves;

a second bypassing conduction means connected to said second charging circuit means for preventing charging of said second capacitor; and

a second bypass controlling means for causing said alternating current of said second charging circuit means to bypass said second capacitor when said engine is rotating in a proper direction for all but one of said half-waves of said alternating current signal which will otherwise charge said second capacitor, and which are produced by said second capacitor charging coil means of said second charging circuit after said ignition timing during each cycle, said one cycle having a duration from a certain ignition timing signal to next ignition timing signal and starting from the point where said second capacitor begins charging.

12. An ignition system as set forth in claim 11

40 wherein said second ignition control means is a transformer whose primary winding is connected in parallel with said second capacitor charging coil means and whose secondary winding is connected to said control electrode of said second semiconductor switching means.

13. An ignition system as set forth in claim 11, wherein said second ignition control means includes a timing signal generator having signal coil means coupled to said magneto generator for producing a sequence of ignition signals during rotation of said magneto generator; and inductor means, mounted in said magneto generator for inducing said ignition timing signal in said second signal coil means.

14. An ignition system as set forth in claim 13, wherein said second bypass controlling means includes second inductor means mounted in said magneto generator for inducing in said second signal coil means a control signal.

15. An ignition system as set forth in claim 11, wherein said second bypass controlling means is said capacitor charging coil means.

16. An ignition system as set forth in claim 11 wherein said second capacitor charging coil means comprises two coils wound on different cores mounted in said magneto generator.

17. An ignition system as set forth in claim 11 wherein said bypass controlling means comprises;

signal generating means mounted in said magneto generator; and
a transformer connected in said second charging circuit means, and said second bypass controlling means comprises;
further signal generating means mounted in said magneto generator; and
a transformer connected in said second charging circuit means.

18. An ignition system as set forth in claim 1 further comprising:

second charging circuit means including a second capacitor charging coil means coupled to said magneto generator for generating an alternating current signal during rotation of said magneto generator, a second rectifying means for rectifying said alternating current signal of said second capacitor charging coil means to produce half-waves and a second capacitor said second coil means, second rectifying means and second capacitor being connected in series to permit current flow from said second capacitor charging coil means through said second capacitor;

a second discharging circuit means connected said second capacitor to said semiconductor switching means having said control electrode and a primary winding of a second ignition coil having said primary winding and a secondary winding, said second capacitor, switching means and second primary winding being connected in series to cause the stored charge on said second capacitor to discharge through said primary winding of said second ignition coil upon conduction of said switching means;

a second spark plug connected to said secondary winding;

second bypassing conduction means connected to said second charging circuit means for preventing charging of said second capacitor; and

a second bypass controlling means for causing said alternating current signal of said second capacitor charging coil means to bypass said second capacitor through said second bypassing conduction means both when said engine is rotating in a proper direction for all but one of said half-waves of said alternating current signal, which will otherwise charge said second capacitor, and which are produced by said second capacitor charging coil means after said ignition timing signal during each cycle, said cycle having a duration from a certain ignition timing, to next ignition timing signal and starting from the point where said second capacitor begins charging.

19. An ignition system as set forth in claim 1, further comprising:

a second charging circuit means including means connecting a second capacitor to said capacitor charging coil means, a second rectifying means for rectifying said alternating current signal and said second capacitor, said charging coil means, second rectifying means, and second capacitor being connected in series to permit current flow from said capacitor charging coil means through said second capacitor;

5

a second discharging circuit means connected to said second capacitor, including a second semiconductor switching means having a control electrode and a primary winding of a second ignition coil having said primary winding and a secondary winding, said second capacitor, second switching means and second primary winding being connected in series to cause the stored charge on said second capacitor to discharge through said primary winding of said second ignition coil upon conduction of said second switching means;

second spark plug connected to said secondary winding;

second bypassing conduction means connected to said second charging circuit means for preventing charging of said second capacitor; and

second bypass controlling means for causing said alternating current of said capacitor charging coil means to bypass said second capacitor through said second bypassing conduction means when said engine is rotating in a proper direction for all but one of said half-waves of said alternating current signal, which will otherwise charge said second capacitor, produced at said capacitor charging coil means after said ignition timing signal during each cycle, said cycle having a duration from a certain ignition timing signal to next ignition timing signal and starting from the point where said second capacitor begins charging.

20. An ignition system as set forth in claim 1, further comprising:

a second discharging circuit means connected to said capacitor including a second semiconductor switching means having a control electrode and a primary winding of second ignition coil having said primary winding and a secondary winding, said capacitor, second switching means and second primary winding being connected in series to cause the stored charge on said capacitor to discharge through said primary winding of said second ignition coil upon conduction of said second semiconductor switching means;

a second spark plug connected to said secondary winding of said second ignition coil;

a second bypassing conduction means connected to said second charging circuit means for preventing charging of said capacitor; and,

a second bypass controlling means for causing said alternating current signal of said capacitor charging coil means to bypass said capacitor through said second bypassing conduction means when said engine is rotating in a proper direction for all but a selected number less than all of said half-waves of said alternating current signal, which will otherwise charge said capacitor, and which are produced by said second capacitor charging coil means after said ignition timing signal during each cycle, said cycle having a duration from a certain ignition timing signal to next ignition timing and starting from the point where said capacitor begins charging.

UNITED STATES PATENT OFFICE
CERTIFICATE OF CORRECTION

Patent No. 3,903,862 Dated September 9, 1975

Inventor(s) Masao Nagasawa

It is certified that error appears in the above-identified patent and that said Letters Patent are hereby corrected as shown below:

In the grant (ONLY) insert sheet 18, as shown on the attached page.
